(57) **CLAIM**

I claim the ornamental design for a speaker LED light ring, as shown and described.

DESCRIPTION

FIG. 1 is a perspective view of a speaker LED light ring, showing a first embodiment of my new design as mounted with a speaker;

FIG. 2 is a perspective view of FIG. 1, illustrated without the speaker;

FIG. 3 is a front elevational view of FIG. 1;

FIG. 4 is a rear elevational view of FIG. 1;

FIG. 5 is a right-side elevational view of FIG. 1;

FIG. 6 is a left-side elevational view of FIG. 1;

FIG. 7 is a top plan view of FIG. 1;

FIG. 8 is a bottom plan view of FIG. 1;

FIG. 9 is a perspective view of a second embodiment thereof as mounted with the speaker;

FIG. 10 is a perspective view of FIG. 9, illustrated without the speaker;

FIG. 11 is a front elevational view of FIG. 9;

FIG. 12 is a rear elevational view of FIG. 9;

FIG. 13 is a right-side elevational view of FIG. 9;

FIG. 14 is a left-side elevational view of FIG. 9;

FIG. 15 is a top plan view of FIG. 9;

FIG. 16 is a bottom plan view of FIG. 9;

FIG. 17 is a perspective view of a third embodiment thereof as mounted with the speaker;

FIG. 18 is a perspective view of FIG. 17 without the speaker;

FIG. 19 is a front elevational view of FIG. 17;

FIG. 20 is a rear elevational view of FIG. 17;

FIG. 21 is a right-side elevational view of FIG. 17;

FIG. 22 is a left-side elevational view of FIG. 17;

FIG. 23 is a top plan view of FIG. 17; and,

FIG. 24 is a bottom plan view of FIG. 17.

The broken lines showing a speaker in FIGS. 1, 9, and 17 depict environmental matter and form no part of the claimed design.
